SINGLE ANODE HG ARC RECTIFIER

Joseph Slepian, Pittsburgh, Pa., assignor to Westinghouse Electric & Manufacturing Company, East Pittsburgh, Pa., a corporation of Pennsylvania

Application July 8, 1939, Serial No. 283,471

11 Claims. (Cl. 175—354)

My invention relates to electric discharge valves and has particular relation to electric discharge devices of the pool type.

In pool electric discharge valves of certain types, a continuous condition of ionization is maintained by a keep-alive discharge. The discharge passes between the pool which functions as the cathode of the valve and a keep-alive electrode disposed adjacent to the cathode. The intensity of the keep-alive discharge governs the ionization within the valve and, therefore, determines the facility with which an arc is ignited between the anode and the cathode.

Because of the ionization maintained in the valve by the keep-alive discharge, the possibility of frequent backfire is considerably increased. To suppress the tendency to backfire, the discharge valve is customarily provided with shields which are disposed adjacent to the anode. The electrostatic effect produced by the shields decreases the number of backfires, but at the same time, it also increases the cathode reluctance of the valve and the valve often fails to fire in the forward direction when it should. An increase in the keep-alive discharge current suppresses the failure to fire in the forward direction, but it enhances the tendency to backfire. Additional shielding which decreases the tendency to backfire again increases the uncertainty of the firing in the forward direction. The advantages of shielding and increasing the keep-alive discharge are thus counteracted by concomitant disadvantages so that a satisfactory valve cannot be attained by merely relying on the improvements introduced by changing these features.

It is, accordingly, an object of my invention to provide a discharge valve of the keep-alive type in which there shall be no uncertainty in the firing of the forward arc while the tendency to backfire shall be suppressed.

Another object of my invention is to provide an electric discharge valve of the keep-alive type, having sufficient shielding to prevent backfire, that shall, without fail, fire in the forward direction when expected to do so.

An ancillary object of my invention is to provide an arrangement for maintaining a discharge in an electric discharge valve of the keep-alive type in which the power consumed in the keep-alive circuit shall be a minimum.

More concisely stated, it is an object of my invention to provide a keep-alive circuit for an electric discharge valve that shall assure the proper ignition of a main arc in the valve.

In accordance with my invention, the current flow through the keep-alive discharge is responsive to the potential impressed between the anode and the cathode of the valve. The relationship between the keep-alive current and the anode-cathode potential is such that the keep-alive current is increased when the forward firing is to take place and decreased when backfire may occur.

The novel features that I consider characteristic of my invention are set forth with particularity in the appended claims. The invention itself, however, both as to its organization and its method of operation, together with additional objects and advantages thereof, will best be understood from the following description of the specific embodiments when read in connection with the accompanying drawings, in which:

Figure 1 is a diagrammatic view showing a preferred embodiment of my invention,

Fig. 2 is a diagrammatic view showing modifications of my invention, and

Fig. 3 is a diagrammatic view showing the structure of the tube of Figs. 1 and 2 in larger scale.

The apparatus shown in Fig. 1 comprises an electric discharge valve 3 through which a load 5 of any general type is supplied from alternating-current-line conductors 7. The line conductors 7 may be energized from the usual commercial 60-cycle generator (not shown).

The electric discharge valve 3 comprises a hollow flanged cylinder 9 of steel or other suitable metal, to the lower rim of which a metallic plate 11 is soldered in such manner that the joint between the plate and the cylinder is gas-tight. A pool 13, preferably of mercury, rests on the plate 11 and functions as the cathode of the valve. A metallic ring 15 is securely fastened to the flange 17 of the cylinder. The ring rests on a rubber gasket 19 and when the bolts 21 securing the ring to the flange are tightened, the junction region between the flange 17 and the ring 15 is gas-tight. An elongated porcelain sleeve 23 passes through the opening in the ring 15 and extends well within the cylinder 9. The sleeve is provided with a shoulder 25 near its central portion and is supported on a flanged annular bracket 27 which is bolted to the ring and on the central portion of which the shoulder rests. The ring 15 has an inner shoulder 29 which tightly abuts the upper surface of the central shoulder 25 on the sleeve 23 with a gasket 31 of rubber or other suitable material interposed between the two surfaces.

Near its center the ring 15 has a groove 33 in which the flange 35 of a metallic sleeve 37 soldered to the porcelain sleeve 23 engages. The metallic sleeve 37 is soldered to the ring 15 within 5 the groove 33.

The anode stem 39 which is in the form of a metallic rod to the end of which the anode 41 is secured, passes through the porcelain sleeve 23 and extends into the cylinder 8 below the 10 sleeve. The upper end 43 of the stem 39 is threaded and a plurality of terminal washers 45 for clamping the anode supply lead are in engagement with the thread. Below the upper threaded portion 43 there is a threaded region 15 47 of increased diameter. A flanged nut 49 is screwed on the latter thread 47 in such manner that its flange 51, which is turned over, engages the upper rim of the porcelain sleeve 23. Below the threaded portion 47 the stem 39 has a shoulder 53 which abuts a gasket 55 disposed on the upper end of the insulator 23. The nut 49 is tightly screwed on the stem and the junction between the flange 51 and the insulator 23 is soldered so that the joint is completely gas-tight. 20

To further seal the arrangement, the stem 39 is provided with another shoulder 57 below the one adjacent to the thread 47. The latter tightly engages an inwardly extending shoulder 59 of the insulator 23 and a gasket 61 is interposed 25 between the two.

The anode shield 63 is of composite structure. It comprises a hollow metal cylinder 65 from the lower rim of which a metallic screen 67 in the form of a segment of a sphere is suspended. The 30 segment 67 screens the lower surface of the anode 41 entirely from the mercury 13. A short cylinder 69 of metal is welded along the upper end of the first cylinder 65, and to the former a metal ring 71 in the form of an open truncated cone is 35 welded. The two cylinders 65 and 69 are welded at their upper ends to a flanged ring 73. The ring 73 is provided with a short central portion 75 which is round along the inner edge and extends downwardly to engage a trough-shaped 40 shoulder 77 near the lower end of the insulating sleeve 23. A spring washer 79 is disposed between the upper rim of the flanged ring 73 and a downwardly extending shoulder 81 on the insulator 23 and holds the shield 63 firmly in engagement 45 with the insulator. The inner cylinder 69 of the shield 63 extends to a point just below the lower end of the insulator 23 and the truncated conical ring 71 is disposed between the insulator 23 and the upper rim of the anode 41.

Near its lower end, the enclosing cylinder 9 is provided with an opening from which a short flanged cylindrical stem 83 extends. The stem 83 may be integral with the cylinder 9 or may be welded or soldered thereto. A flanged porcelain 50 tube 85 is bolted tightly between the flange 87 of the stem 83 and a disc 89 parallel to the flange. The outer surface of the flange 87 and the inner surface of the disc 89 are grooved and the flange 91 of the tube 85 is disposed in the grooves with 55 rubber gaskets 93 interposed on each side between the porcelain and the adjacent surface. The central portion 95 of the tube 85 extends for a short distance along the stem 83.

A metallic rod 97 which is bent over at right 60 angles at its free end and carries a graphite tip 99 extends horizontally from the disc 89. The rod 97 is insulated from the stem 83 by the flanged porcelain cylinder 85. It is protected against the discharge heat and the mercury vapor by a sleeve 75 101 of quartz which extends from the disc 89 to

the tip 99. The tip 99 is only a short distance above the mercury 13 and a rod 103 of boron carbide, silicon carbide, or a similar substance is secured to the graphite tip 99 and dips into the mercury. The rod 103 functions as a make-alive 5 electrode and the tip 99 as a keep-alive electrode. When sufficient current flows through the rod 103, a discharge is ignited between the tip 99 and the mercury 13. The discharge short-circuits the current flow through the rod 103 and if it is energized from a direct current source, it continues to supply ions for the main discharge in the valve 3.

The valve 3 may be completely sealed off against the outside atmosphere. In many cases, it is 15 maintained evacuated by a pump system which is in communication with the interior of the valve. The make-alive electrode need not, of course, be a rod 103 as described hereinabove. It may be of any type now well known in the art; 20 for example, a magnetically operated plunger which produces mercury spray in the region of the keep-alive electrode 99 may be used.

The make-alive current is supplied and the 25 keep-alive discharge is sustained from a full-wave rectifier 105 energized from the main line conductors 1. The positive terminal 107 of the rectifier is connected to the disc 89 through a suitable current limiting resistor 109 and its negative terminal 111 is connected to the lower plate 11 30 on which the mercury pool 13 is disposed. Normally, the make-alive discharge current is maintained at a value such as to preclude the possibility of backfire between the anode 41 and the cathode 13. Discharge current of this magnitude 35 is, however, not sufficient to, at all times, assure the ignition of a forward arc. In accordance with my invention, the discharge is enhanced from the main line conductors 1 when the polarity of the anode-cathode potential is proper for ignition. 40

The increase in the keep-alive discharge current is attained by connecting a half-wave rectifier 113 of any suitable type between the anode 41 and the keep-alive electrode 99. The anode 115 of the rectifier is connected to the anode 41 45 of the main valve and the cathode 117 to the keep-alive electrode. When the anode-cathode potential impressed on the valve 3 is negative, the current flowing in the keep-alive discharge is supplied only through the full-wave rectifier 50 105 and, therefore, is relatively small. Under such circumstances, backfire does not occur. When the anode-cathode potential of the main discharge valve 13 becomes positive, current first flows through the half-wave rectifier 113 and between the keep-alive electrode 99 and the cathode 13. 55 The keep-alive discharge current is thus increased to a sufficient value to assure the ignition of a forward discharge. When the forward arc is ignited, the current flow through the 60 rectifier 113 is materially reduced because the potential drop across the main discharge is relatively small.

The half-wave rectifier 113 may be of any general type. Where the additional current required 65 is not excessive, a dry rectifier or a high-vacuum rectifier may be used. Where the additional keep-alive current is relatively large, the rectifier should be of the arc-like type.

In the modification shown in Fig. 2, the increase 70 in keep-alive current is produced by short-circuiting a portion 119 of the resistor 109 in the keep-alive circuit at the instant when the polarity of the anode-cathode potential is proper for ignition. An auxiliary electric discharge valve 121 of the 75

type having a control electrode 122 is connected across the portion 119 of the resistor 109 which is to be short-circuited. The anode 123 of the auxiliary valve 121 is connected to the positive terminal 107 of the full wave rectifier 105 and its cathode 124 to an intermediate tap 125 of the resistor 109. A voltage divider 126 of relatively high resistance is connected between the anode 41 and cathode 13 of the main discharge valve 3. The control electrode 123 of the auxiliary discharge device is connected to the intermediate tap 127 of the voltage divider. Where the auxiliary valve is of the arc-like type as is, in general, the case, it is desirable that the anode-cathode potential supplied thereto shall fall to zero periodically. For this reason, the filter 129 utilized in connection with a full-wave rectifier 105 is interposed between the keep-alive electrode 99 and the resistor 109 and not between the rectifier 105 and the resistor 109 as in the Fig. 1 system.

The anode-cathode potential which is normally impressed on the auxiliary discharge valve 121 is the potential drop across the portion 119 of the current limiting resistor 109 which arises by reason of the keep-alive current flow produced by the rectifier 105. The potential impressed between the control electrode 122 and the cathode 124 of the auxiliary valve consists of a negative component produced by the potential drop across the portion of the resistor 109 between the intermediate tap 125 and the keep-alive electrode 99 and a component of changing polarity impressed by the portion of the voltage divider 126 between the cathode 13 of the main valve 3 and the tap 27 to which the control electrode 122 is connected. When the anode-cathode potential impressed on the main valve 3 is negative, its cathode 13 is at a positive polarity relative to its anode 41 and the keep-alive electrode 99 is, therefore, more positive than the intermediate tap 127 of the divider 126. The potential impressed between the control electrode 122 and the cathode 124 of the auxiliary valve 121 from the divider 126 is, therefore, at this time, negative and the auxiliary valve is non-conductive. When the anode-cathode potential impressed on the main valve 3 becomes positive, the potential supplied by the voltage divider reverses in polarity and the auxiliary valve 121 becomes conductive and short-circuits the portion 119 of the current limiting resistor 109 so that the additional current is supplied in the keep-alive circuit. The auxiliary valve is rendered non-conductive at the end of every half-cycle during which it conducts current because its anode-cathode potential falls to zero.

Although I have shown and described certain specific embodiments of my invention, I am fully aware that many modifications thereof are possible. My invention, therefore, is not to be restricted except insofar as is necessitated by the prior art and by the spirit of the appended claims.

I claim as my invention:

1. In combination, an electric discharge valve having a cathode of the pool type, a keep-alive electrode cooperative with said cathode and a charge-collecting electrode, means for continuously maintaining current flow of a substantial magnitude between said keep-alive electrode and said cathode, means for impressing a potential between said charge-collecting electrode and cathode and means responsive to said potential

for varying the current flow between said keep-alive electrode and said cathode.

2. In combination, an electric discharge valve having a cathode of the pool type, a keep-alive electrode cooperative with said cathode and a charge-collecting electrode, means for continuously maintaining current flow of a substantial magnitude between said keep-alive electrode and said cathode, means for impressing a potential between said charge-collecting electrode and cathode and means responsive to said potential for increasing the current flow between said keep-alive electrode and said cathode to a magnitude such as to expedite ignition of an arc between said collecting electrode and said cathode when said potential attains the proper magnitude for the ignition of such an arc.

3. In combination an electric discharge valve having a cathode of the pool type, a keep-alive electrode cooperative with said cathode and a charge-collecting electrode, means for continuously maintaining current flow of a substantial magnitude between said keep-alive electrode and said cathode, means for impressing alternating potential between said charge-collecting electrode and cathode and means responsive to said potential for increasing the current flow between said keep-alive electrode and said cathode to a magnitude such as to expedite ignition of an arc between said collecting electrode and said cathode when said potential attains the proper polarity for the ignition of such an arc.

4. In combination an electric discharge valve having a cathode of the pool type, a keep-alive electrode cooperative with said cathode, a charge-collecting electrode, and shielding means cooperative with said collecting electrode for preventing inverse current between said collecting electrode and said cathode, means for continuously maintaining current flow of a substantial magnitude between said keep-alive electrode and said cathode, said shielding means functioning to decrease the tendency to ignite an arc between said collecting electrode and cathode for a given keep-alive current, means for impressing a potential between said charge collecting electrode and cathode and means responsive to said potential for increasing the current flow between said keep-alive electrode and said cathode to a magnitude such as to expedite ignition of an arc between said collecting electrode and said cathode when said potential attains the proper magnitude for the ignition of such an arc.

5. In combination, an electric discharge valve having a cathode of the pool type, a keep-alive electrode cooperative with said cathode, a charge-collecting electrode and shielding means cooperative with said collecting electrode for preventing inverse current flow between said collecting electrode and said cathode, means for continuously maintaining current flow of a substantial magnitude between said keep-alive electrode and said cathode, means for impressing a potential between said charge-collecting electrode and cathode, said shielding means functioning to decrease the tendency to ignite an arc between said collecting electrode and said cathode for a given potential when the keep-alive current has a predetermined magnitude, and means responsive to said potential for compensating for said decrease in the tendency to ignite an arc.

6. In combination, an electric discharge valve having a cathode of the pool type, a keep-alive electrode cooperative with said cathode, a charge

- 5 collecting electrode and shielding means cooperative with said collecting electrode for preventing inverse current flow between said collecting electrode and said cathode, means for continuously maintaining current flow of a substantial magnitude between said keep-alive electrode and said cathode, means for impressing a potential between said charge-collecting electrode and cathode, said shielding means functioning to decrease the tendency to ignite an arc between said collecting electrode and said cathode for a given potential when the keep-alive current has a predetermined magnitude, and means responsive to said potential for increasing the keep-alive current flow to compensate for said decrease in the tendency to ignite an arc.
- 10 7. In combination an electric discharge valve having a cathode of the pool type, a keep-alive electrode cooperative with said cathode and a charge-collecting electrode, means for continuously maintaining current flow of a substantial magnitude between said keep-alive electrode and said cathode, means for impressing a potential between said charge-collecting electrode and cathode, and auxiliary electric discharge valve means interposed between said collecting electrode and said make-alive electrode for varying the current flow between said keep-alive electrode and said cathode.
- 15 8. In combination, an electric discharge valve having a cathode of the pool type, a keep-alive electrode cooperative with said cathode and a charge-collecting electrode, means for maintaining current flow of a predetermined magnitude between said keep-alive electrode and said cathode, means for impressing a potential between said charge-collecting electrode and cathode, and current rectifying means interposed between said collecting electrode and said make-alive electrode, in such a manner as to conduct current in the same direction as the normal current flow between said anode and cathode, for varying the current flow between said keep-alive electrode and said cathode.
- 20 9. In combination, an electric discharge valve
- 25 having a cathode of the pool type, a keep-alive electrode cooperative with said cathode, a charge-collecting electrode and shielding means cooperative with said collecting electrode for preventing inverse current flow between said collecting electrode and said cathode, means for maintaining current flow of a predetermined magnitude between said keep-alive electrode and said cathode, means for impressing a potential between said charge-collecting electrode and cathode, said shielding means functioning to decrease the tendency to ignite an arc between said collecting electrode and said cathode for a given potential when the keep-alive current has a predetermined magnitude, and means includ- 10 ing a rectifier having an anode connected to said collecting-electrode and a cathode connected to said keep-alive electrode for compensating for said decrease in the tendency to ignite.
- 30 10. In combination, an electric discharge valve having a cathode of the pool type, a keep-alive electrode cooperative with said cathode, a charge-collecting electrode and shielding means cooperative with said collecting electrode for preventing inverse current flow between said collecting electrode and said cathode, means for continuously maintaining current flow of a substantial magnitude between said keep-alive electrode and said cathode, means for impressing alternating potential between said charge-collecting electrode and cathode, said shielding means functioning to decrease the tendency to ignite an arc between said collecting electrode and said cathode for a given potential when the keep-alive current has a predetermined magni- 25 tude, and means responsive to said potential for compensating for said decrease in the tendency to ignite an arc.
- 35 11. In an electric discharge valve having a cathode of the pool type, a keep-alive electrode and means for transmitting through said electrode current varying periodically between a maximum value and a maximum value which is substantially greater than zero.
